Edward Richards of Hingham Massachusetts
Letters Patent (Patented June 28, 1836)

The Schedule referred to in these Letters Patent, and making part
of the same containing a description in the words of the said Ed-
ward Richards himself of his improvement in the construction
and form of the Drawing Knife.

To all people to whom these presents shall come, Be it known
that Edward Richards of Hingham in the County of Plymouth
and Commonwealth of Massachusetts, machinist, have invented
a new and useful improvement in the construction and form
of the Drawing Knife, the Instrument whereby Holes are
and other works in wood, and that the following is a full
and accurate description thereof.

Richard's Conical Drawing Knife. The improvement of
this Drawing Knife over those in common use consists
First, in making the blade of the knife conical on both
sides. Second, in attaching the handles of this instrument
to the ends thereof by a screw and nut, by which they may
be taken off, reversed and placed upon the instrument
again so as to use both sides of the knife.

The advantages of the improvement are. First, The con-
ical blade causes less friction than the convex or plane blade
and consequently works with greater ease and celerity.
Second - Being 25 degrees from the horizontal instrument
is more easily sharpened. Third, by the movable handles
the instrument may be used on both sides, so that it will
wear equally on both sides when used.

I declare that I claim as my own invention and
not previously known in the above described improvement,
as, First, the conical blade and second the movable han-
dles by which the advantages before mentioned are obtained.
